UNITED STATES PATENT OFFICE.

ETHAN ROGERS, OF BALLSTON, NEW YORK.

DESIGN FOR A HATCHET.

SPECIFICATION forming part of Design No. 25,358, dated April 7, 1896.

Application filed February 7, 1896. Serial No. 578,448. Term of patent 14 years.

To all whom it may concern:

Be it known that I, ETHAN ROGERS, a citizen of the United States, residing at Ballston, county of Saratoga, State of New York, have 5 invented and produced a new and original Design for Hatchets, of which the following is a specification, reference being had to the accompanying drawing, which shows a view in perspective of a hatchet embodying my 10 novel design.

The leading features of my design consist in depressed concave surfaces on two opposite sides of the head-shank, the plane surfaces being connected by each concave surface and a concaved or outwardly and downwardly curved surface on one or both edges of the bit-shank.

A is the poll or eye of the hatchet.

A' is the head, and A² the bit.

20 B is the head-shank, which connects the head with the poll; and C the bit-shank, which connects the bit with the poll.

The head-shank is provided with two oppositely-located depressed or concaved surfaces 25 B', and the oppositely-located plane surfaces B², connected with each other by each concave surface. The bit-shank is provided on its

front and rear edges with the concaved or outwardly and downwardly curved surface, which connects outwardly and downwardly 30 35 extended plane surfaces on the similar edges of the bit with the poll.

That one of the leading features of my design which is found on the bit-shank would not be essentially changed if one of the edges 35 of the bit were made plane, as indicated by the dotted line.

What I claim as new, and desire to secure by Letters Patent, is—

1. The design for a hatchet herein shown 40 and described.

2. In a design for a hatchet, the design for a head and head-connecting shank, herein shown and described.

3. In a design for a hatchet, the design for 45 a bit and bit-connecting shank, herein shown and described.

In testimony whereof I have hereunto set my hand this 3d day of February, 1896.

ETHAN ROGERS.
